UNITED STATES PATENT OFFICE.

MICHAEL F. KELLEY, OF STOUGHTON, MASSACHUSETTS.

ARCH-SUPPORTING SHOE.

1,177,777.

Specification of Letters Patent.

Patented Apr. 4, 1916.

Application filed July 29, 1912. Serial No. 711,975.

To all whom it may concern:

Be it known that I, MICHAEL F. KELLEY, a citizen of the United States, and resident of Stoughton, in the county of Norfolk and

5 State of Massachusetts, have invented certain new and useful Improvements in Arch-Supporting Shoes, of which the following is a specification.

Numerous attempts have been made to 10 remedy "broken arches" so-called, and to this end numerous arch supports of various kinds have been suggested or produced, the same to be employed inside of the shoe so as to directly engage and support the under 15 portion of the foot. In many instances, these have proved to be not only exceedingly uncomfortable but have failed in their purpose. I have found that, as a practical matter, the best results can be secured by 20 so constructing the shoe that the necessary support is afforded thereby, and to this end I use a resilient spring located exteriorly of the shoe under the shank, springs being supplied in varying degrees of curvature and 25 stiffness for people of different weight. By thus locating the arch-supporting spring, the shoe is made much more comfortable, may be fitted accurately on the wearer's foot, and may be caused to fit well into 30 the arch and support it.

On the accompanying drawings—Figure 1 illustrates a shoe embodying the invention. Fig. 2 represents a bottom view of the same. Fig. 3 illustrates the sole prior to the at- 35 tachment of the upper. Fig. 4 illustrates one of the arch-supporting springs. Fig. 5 represents an enlarged section on the line 5—5 of Fig. 2 and shows means for securing the spring in place.

40 It will be understood that the invention is applicable not only for MacKay sewed shoes but also for welt shoes, the illustration of the shoe in Fig. 1 being substantially conventional, merely for the purpose of illustrating the location of the fastener for securing the spring in place. As thus shown, the shoe includes the sole *a*, the insole *b* and heel *c*. In constructing the shoe, at a point substantially midway between its ends or 45 near the ball of the foot, a hole 10 is formed in the tread surface of the sole, and then, by a milling cutter or other tool a groove 11 is

formed, the groove lying substantially in the median line of the sole and extending to a point where it will be covered by the heel, so that when the shoe is formed, the slot or groove will be located under the arch. After the sole has been molded into shape and the upper has been attached in either of the usual ways, a spring *d* is placed in the 55 groove so as to lie flush with the surface of the sole. This spring is preferably made of steel and is preferably nickel-plated so as not to detract from the appearance of the shoe. At one end, the spring is provided with a depressed annulus *d'* which fits in the hole 10, and this end of the spring is fixed in place by any suitable form of fastening device. A fastener which I may employ is 60 illustrated in Figs. 5 and 6 consisting of two 65 complementary members *e* and *f*. The member *e* consists of a stud having a head 12 and an internally threaded shank 13; and the member *f* consists of a screw adapted to pass through an aperture *d*² in the spring and to be screwed into the shank of the 70 member *e*. The head 14 of the member *f* is thus located within the annular socket formed in the spring so that it is flush with or above the surface of the sole. The insole may be 75 formed with a shallow hole to receive the head 12 so that the head will lie flush with the insole. To prevent the passage of water through the aperture thus formed in the bottom of the shoe, I use a washer *g* of 80 rubber or other material, shown in Fig. 5. When the heel is secured in place, the free end of the spring is supported thereby but is free to move relatively to the heel, and the heel end of the shoe. To prevent its 85 binding, the free end of the spring has a 90 slightly curved portion *d*³.

95 By varying the curvature of the spring, it will be apparent that the shank portion of the shoe may be caused to assume any degree of curvature so that the arch portion of the foot will be properly supported by the shank of the shoe; and, by varying the thickness or degree of elasticity of the springs, the shoes may be adapted for persons of different weights. As the pressure upon the spring increases and decreases, as 100 when a person is walking, the free end of the spring may slip back and forth in its

socket so that the shoe possesses a marked degree of flexibility.

While I have described the spring as being attached to the shoe in the process of manufacture thereof, it is quite apparent that merely by removing the heel, any shoe already manufactured may be equipped with my arch supporting spring, the heel being subsequently replaced.

10 It will be understood that in any event the springs are strong enough to bend the leather sole so as to cause it to assume substantially the curvature of the spring itself. Consequently the curvature of the shank 15 portion of the sole does not depend upon the molding operation to which the sole is subjected prior to its attachment to the upper. Moreover the springs may be attached to a partially worn shoe so as to raise the 20 shank portion to the curvature desired. When a shoe has become worn, the spring may be easily detached to permit the repair of the shoe and subsequently secured again in position. The width of the spring may 25 vary of course and its length may be more or less increased or decreased.

By reason of the ease with which these springs may be attached and detached, it is apparent that a person suffering with a 30 badly broken arch may have his shoes from time to time equipped with springs of greater curvature so that the metatarsal arch will be gradually caused to assume a normal position. This may be accomplished by the 35 wearer of the shoe without the necessity of taking the shoe to a cobbler or shoemaker, since the only tool required for the attachment or detachment of the spring is an ordinary screw-driver.

40 Having thus explained the nature of my said invention and described a way of mak-

ing and using the same, although without attempting to set forth all of the forms in which it may be made or all of the modes of its use, what I claim is:

1. The combination with a shoe, of a 45 spring metal arch support arranged against the lower surface of the outsole, and a detachable fastener arranged to fasten the front end of said support to the outsole, the rear end of said support being arranged between the heel and the heel-seat of said outsole and being capable of slipping longitudinally to compensate for flexure.

2. A shoe comprising in combination, a 50 heel, an outsole having a recess in its lower surface extending longitudinally in the shank portion to a point in the rear of the breast of said heel, a spring metal arch support arranged in said recess, and a fastener 55 arranged to fasten the front end of said support to said outsole, the rear end of said support being capable of slipping longitudinally to compensate for flexure.

3. An arch-supporting shoe, comprising 60 an outer sole and a heel, the outer face of the shank of the sole being grooved substantially from the ball to a point above the heel, a detachable arch-supporting spring 65 located in said groove with a free end between the heel and outer sole, said spring having a recess at its other end, a removable fastener passed through said spring into said sole and having a head located in 70 said recess, and a flat head on the interior of 75 the shoe.

In testimony whereof I have affixed my signature, in presence of two witnesses.

MICHAEL F. KELLEY.
